(57) **CLAIM**

The ornamental design for wildlife pond steps, as shown and described.

DESCRIPTION

FIG. 1 is a front, left-side perspective view of a wildlife pond steps showing my new design;

FIG. 2 is a left side view thereof, the right side view being a mirror image thereof;

FIG. 3 is front side view thereof;

FIG. 4 is a top plan view thereof;

FIG. 5 is a left-side cross-sectional view thereof; and,

FIG. 6 is an enlarged view of the encircled portion identified as 6 in FIG. 1.

The broken lines shown in the drawings depict portions of the wildlife pond steps and form no part of the claimed design.
